A. E. ROPE,
COMBINATION FACE BRUSH,
APPLICATION FILED DEC. 31, 1921.

1,422,787.

Patented July 11, 1922.

UNITED STATES PATENT OFFICE.

ARTHUR E. ROPE, OF BROOKLYN, NEW YORK.

COMBINATION FACE BRUSH.

1,422,787.

Specification of Letters Patent. Patented July 11, 1922.

Application filed December 31, 1921. Serial No. 526,088.

To all whom it may concern:

Be it known that I, ARTHUR E. ROPE, a citizen of the United States, and a resident of the city of New York, borough of Brooklyn, in the county of Kings and State of New York, have invented a new and Improved Combination Face Brush, of which the following is a full, clear, and exact description.

- 10 This invention relates to improvements in combination face brushes, an object of the invention being to provide a device which provides all the apparatus necessary for the care of the face before and after shaving.
- 15 A further object is to provide a device of the character described which embodies a shaving brush, a massage device, a shaving stick, a container for talcum powder and the like, a container for massage cream and 20 the like, devices for applying the powder and the cream, covers for said receptacles, and all of said parts embodied in a single member which is separable to permit the proper functioning of the elements thereof.
- 25 A further object is to provide a device of the character stated, which will be neat and attractive in appearance, which will be sanitary in use and which will occupy but relatively small space, but may be conveniently 30 stored or carried in the travelling bag of the user.

With these and other objects in view the invention consists in certain novel features of construction, and combinations and arrangements of parts, as will be more fully hereinafter described and pointed out in the claims.

In the accompanying drawings—

Figure 1 is a view in longitudinal section 40 illustrating my improved combination face brush.

Figure 2 is a view in side elevation thereof.

Figure 3 is a view in transverse section 45 on the line 3—3 of Figure 1.

My improved combination face brush comprises four separable members 1, 2, 3 and 4. All of these members 1, 2, 3 and 4 are of the same external diameter and cylindrical in form, and having interlocking separable engagement which will be more fully hereinafter described, to form a single continuous cylindrical body, which may be of rubber, metal, or any other suitable material.

The member 3 constitutes a brush body

having secured thereto at one side the assemblage of bristles constituting a brush 5, and on its other side having secured or integrally formed a plurality of flexible tabs 60 or fingers 6 constituting a massage device.

The brush body 3 is, at one side, recessed and internally screw threaded, as shown at 7, for the reception of the screw threaded end of the member 2, the latter constituting 65 a handle for the brush 5. This member or handle 2 is divided by a partition 8 into two compartments, the smaller compartment 9 at one end enclosing the massage device 6, and the larger compartment, which is at the 70 other end of the handle, constituting an enclosure for a stick of shaving soap 11.

The member 1 constitutes a receptacle for talcum or other powder 12 and is formed at one end with a screw threaded ring 13 having screw threaded engagement as shown at 75 14, with the outer end of the handle 2. This ring 13 is internally screw threaded, as shown at 15, into which the threaded end of the shaving stick 11 is screwed and held, so 80 that it is removable with the member 1. A closure 16 is screwed on to the threaded outer end of the member 1, as shown at 17, so as to form a closure for the member 1, and a powder puff 18 is fixed to the closure 85 16 and removable therewith.

The member 4 is divided by a partition 19 and one end of said member 4 constitutes a cover or enclosure for the brush 5 and has screw threaded engagement with the member 3, as shown at 20. This member 4 is formed with a circular series of slots or openings 21 to admit a circulation of air in contact with the brush to permit the latter to dry and prevent mold. The extreme 90 end of the member 4 constitutes a receptacle for massage paste 22 and a closure 23 is screwed on to the end of the massage cream receptacle, as shown at 24, and carries a sponge or other device 25 to apply the massage cream to the face.

The outer surfaces of the members are provided with milled or roughened portions 26 to facilitate their turning movement and both closures 16 and 23 have also milled surfaces for a like purpose.

The operation of my improved device is as follows:

It will be noted that when the cover 4 is removed, the members 1 and 2 will constitute a handle for the brush 5 and permit the latter to be employed as any ordinary

shaving brush is employed. When it is desired to use the shaving stick 11, the member 1 is unscrewed from member 2 and carries with it the stick 11 and after the latter 5 has been used, it is enclosed within the member 2 and the members 1 and 2 connected as before. When it is desired to use the massage device 6, the member 2 is unscrewed from the member 3 with the member 4 operating 10 as a handle for the massage device, and when the talcum powder 12 or the massage cream 22 is to be used, their respective closures 16 and 23 are removed and the contents applied by means of the powder puff 18 15 or the sponge 25, as will be readily understood.

It will thus be seen that in a single device I embody all of the essential devices or elements which are desirable in use in connection 20 with the treatment of the face in shaving, and provide such devices in a small compact, neat appearing and attractive device.

Furthermore, such device readily appeals 25 to the user because it will result in economy of space, particularly to a travelling man, as he can carry with him in a single device a multiplicity of toilet accessories which can be stored in a small space in his travelling 30 bag.

Various slight changes might be made in the general form and arrangement of the parts described without departing from the invention, and hence I do not limit myself to 35 the precise details set forth, but consider myself at liberty to make such changes and

alterations as fairly fall within the spirit and scope of the appended claims.

I claim:

1. As a new article of manufacture, a 40 combination face brush comprising a body having a brush at one side and massage devices at the other side, covers having screw threaded engagement with the body and covering the brush and the massage device re- 45 spectively, one of said covers having a receptacle at one end, a member having screw threaded engagement with the other of said covers and adapted to support a shaving stick, said last-mentioned member also constituting a receptacle, removable closures 50 for said receptacles, a powder puff secured to one of said covers, and a sponge to the other of said closures.

2. As a new article of manufacture, a 55 combination face brush comprising a cylindrical body having a brush attached to one end and a massage device to the other end, covers for mounting on the body to enclose the brush and the massage device, re- 60 spectively, one of said covers having a receptacle provided in one end, a closure having a powder puff attached thereto provided to close said receptacle, a casing having a chamber formed therein attached to the 65 other of said covers, means attached to the lower end of said casing for supporting any solid that may be connected to the same, and a closure for closing the chamber provided in the casing mounted on the cover.

ARTHUR E. ROPE.
